CLAIM

The ornamental design for a filling apparatus for a container, as shown and described.

DESCRIPTION

FIG. 1 is a perspective view of a filling apparatus for a container showing the claimed design;
 FIG. 2 is a front elevation view thereof;
 FIG. 3 is a rear elevation view thereof;
 FIG. 4 is a left side view thereof;
 FIG. 5 is a right side view thereof;
 FIG. 6 is a top plan view thereof; and,
 FIG. 7 is a bottom plan view thereof.

The evenly broken lines are shown for the purpose of illustrating parts of the article that form no part of the claimed design.

1 Claim, 4 Drawing Sheets
